TRIPOD ADJUSTABLE BOILER STAND

Filed July 30, 1924

2 Sheets-Sheet 2

UNITED STATES PATENT OFFICE.

HENRY E. DERBYSHIRE, OF PHILADELPHIA, PENNSYLVANIA, ASSIGNOR TO SANITARY COMPANY OF AMERICA, OF PHILADELPHIA, PENNSYLVANIA, A CORPORATION OF DELAWARE.

TRIPOD ADJUSTABLE BOILER STAND.

Application filed July 30, 1924. Serial No. 729,117.

To all whom it may concern:

Be it known that I, HENRY E. DERBYSHIRE, a citizen of the United States, residing at Philadelphia, in the county of 5 Philadelphia and State of Pennsylvania, have invented certain new and useful Improvements in Tripod Adjustable Boiler Stands, of which the following is a specification, reference being had therein to the 10 accompanying drawings.

This invention relates to a tripod adjustable boiler stand, and the object of the invention is the construction of a stand which is provided with simple and efficient 15 interlocking means for positively fastening the parts of the stand together.

Another object of the invention is the construction of a domestic boiler stand the parts of which can be quickly assembled, 20 without the use of auxiliary means, such as bolts, rivets, and the like, and which, when assembled, will be very durable and efficient in use or operation.

With the foregoing and other objects in view, my invention comprises certain novel combinations, constructions and arrangements of parts as will be hereinafter described, illustrated in the accompanying drawings, and more particularly pointed 30 out in the appended claims.

In the drawings:

Figure 1 is a perspective view of an embodiment of this invention.

Figure 2 is a fragmentary, inverted, perspective view of one of the pairs of ears of the body of the embodiment shown in Figure 1.

Figure 3 is an enlarged, fragmentary, perspective view of the central portion of 40 a leg.

Figure 4 is a fragmentary, perspective view of another embodiment of the present invention.

Figure 5 is a fragmentary, perspective view of the leg of the embodiment shown in Figure 4.

Figure 6 is a fragmentary, plan view of the body shown in Figure 4 and illustrating one of the pair of ears extending from 50 the body.

Figure 7 is a fragmentary, perspective view of another embodiment of the present invention.

Figure 8 is a fragmentary, plan view of

the body shown in Figure 7, with a pair of 55 ears extending therefrom.

Figure 9 is a fragmentary, perspective view of one of the lugs of the embodiment shown in Figure 7.

Referring to the drawings by numerals, 60 1 designates the body of the boiler stand, which body is provided with ears 2 arranged in pairs, producing bifurcated structures into which portions of the legs 3 are positioned, as hereinafter specifically described. 65

The ears 2 in each pair (Fig. 2) are provided in their base or under face with registering sockets 4 into which said lugs 5 of the leg 3 are adapted to be positioned as clearly illustrated in Fig. 1. The broad 70 portion 6, provided with said lugs 5, has, on its upper edge, an elongated, transversely-extending lug 7; this lug 7 bears against the top edge of the ears 2, preventing any pivotal movement downwardly of 75 the inner, enlarged end 6 of the leg after the particular lug 5 is seated in sockets 4 of the ears, thereby holding the legs and the body securely together with a very simple operation, eliminating the use of any 80 auxiliary fastening means, such as bolts or rivets.

To disassemble the legs from the body all that is necessary is to relieve the load 85 off the stand and move the upper ends of the legs slightly outwardly, whereupon the lugs in the sockets 4 will be moved out of the sockets and then the legs can be slid off the ears.

The boiler is seated or positioned upon 90 the stand with its lower end or edge resting in the receiving notches 8.

In the embodiment shown in Figs. 4 to 6 the body 1 is provided with a plurality of sets of ears 9 and these ears are provided in 95 their upper edge with pairs of parallel sockets 10, these sockets being preferably V-shaped for receiving the elongated V-shaped lug 11 that is formed in substantially the same position on the leg 3 as the lug 7 shown 100 in the embodiment illustrated in Figs. 1 to 3. In the embodiment shown in Figs. 4 to 6, instead of employing the lugs 5, as in Fig. 1, I use ribs 12; these ribs 12 are formed on the opposite faces of the enlarged portion 6 of the leg and have the lower edge of the ears 9 bearing thereon, as shown clearly in Fig. 4, with the transverse lug 11 resting in 105

sockets 10. It is to be noted that lateral adjustment of the legs may be accomplished by placing the lug 11 in different sets of sockets but owing to the efficiency, as well as simplicity of my structure, the interlocking feature produces a structure that an unskilled mechanic can quickly comprehend and which is efficient in fastening the parts of the stand securely in an assembled position.

In the embodiment shown in Figs. 7 to 9, I employ body 1 with the pair of ears 13 between which is positioned the leg 14. Registering V-shaped sockets 15 are formed in the inner faces of ears 13, in which is positioned the V-shaped, vertically-extending ribs 16, which ribs are formed on the broad portion 6 of the leg 14. When the leg 14 is positioned in the ears 13, with the ribs 16 in sockets 15, a very secure and efficient assembling of the parts is accomplished, for as quickly as the legs are assembled with the body so are they fastened in position, ready to receive the boiler.

While I have described the preferred embodiments of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. A boiler stand comprising a body having sets of outstanding ears, the ears of each set being spaced transversely from each

other, standards having their upper ends adapted for supporting engagement with a boiler, arms extending from said standards and adapted to fit between cooperating ears, cross bars extending transversely across the upper edges of the free end portions of said arms to extend across the upper edges of said ears, and abutments extending from the sides of said arms to engage the lower edges of said ears whereby said standards may be tilted and slid radially of the body for adjustment to the size of the boiler to be supported and then swung to a vertical position with the cross bars and abutments engaging the upper and lower edges of said ears and retaining the standards in a set position.

2. A boiler stand comprising a body having sets of outstanding ears, the ears of each set being spaced transversely from each other, standards having their upper ends adapted for supporting engagement with a boiler, arms extending from said standards and adapted to fit between cooperating ears, abutments carried by the free end portions of said arms to extend in crossed engagement with the upper edges of said ears, and abutments extending from said arms to engage the lower edges of said ears, said ears being provided with recesses to receive certain of said abutments and retain the standards in a set position after being moved longitudinally of the ears in an inclined position and returned to a vertical boiler supporting position.

In testimony whereof I hereunto affix my signature.

HENRY E. DERBYSHIRE.
